UNITED STATES PATENT OFFICE

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS

GAS RANGE

Application filed June 13, 1927. Serial No. 198,462.

This invention relates to gas ranges and is more particularly devoted to an improved closed top stove so designed and constructed that the use of four or more burners, in front 5 and rear sets, is rendered thoroughly practical and about the same operating efficiency is secured as with an ordinary open top stove.

Experiments on the present stove showed that the back burners were supplied with too 10 much secondary air because of their close proximity with the outlet to the flue, whereas the front burners were not supplied with quite enough. This tendency was observed when the closed cooking top was allowed to 15 exhaust directly into a flue of a size sufficient for conducting the products of combustion from the oven section. According to the present invention this difficulty is remedied when the flue conduits for the cooking top and for 20 the oven section are determined separately to suit the particular requirements in the two cases. A perfectly balanced operation of all of the cooking top burners is thus obtained when a slight flue restriction is made therefor. 25 Any tendency for the flue to become choked with products of combustion due to the restriction, I have found is entirely avoided by locating the outlet end of the closed top flue conduit directly beneath the intake end of the 30 flue to make available the good draft provided thereby.

The present improvements are clearly illustrated in the accompanying drawings where- 35 in—

Figure 1 is a view of the back of a gas stove having flue connections in accordance with my invention; and

Fig. 2 is a vertical section taken on the line 2—2 of Fig. 1 looking in the direction of the 40 arrows.

The invention is illustrated as applied to gas ranges of the cabinet type, consisting of an oven section 5 provided at one side of a closed cooking top 6. The latter has the usual 45 splasher wall 7 and top shelf 8. The drip pan 9 beneath the closed top provides a secondary air chamber 10 for the burners 11 arranged beneath a distributor plate 12 in accordance with the disclosure in my co-pending applica- 50 tion, Serial No. 193,276, filed May 21, 1927.

In accordance with said application the plate 12 has openings 13 providing communication between the secondary air chamber 10 and a combustion chamber 14. The burners 11, which are supplied with primary air and gas 55 through the manifolds 15 in the usual manner and have connection through cocks 16 with the front manifold pipe 17, are arranged to project the flames therefrom through the openings 13 toward the cooking top. Secondary air is drawn with the flames through the openings into the combustion chamber 14, as fully set forth in said application, the waste products of combustion being arranged to travel rearwardly and out of the combustion 60 chamber through an elongated exhaust opening 18 leading into a neck 19 communicating with the lower end of a flue conduit 20. Experiment on the present stove has shown that in the absence of a specially designed flue as 65 herein contemplated, the back burners on account of being closer to the flue outlet are supplied with too much secondary air and the front burners not quite enough. This difficulty was observed even though all other con- 70 ditions, as regards design and construction in the cooking top itself, were proper to secure perfect combustion at the several burners. Upon analysis it appeared that the trouble 75 was due to the fact that the full sized flue used for the oven section afforded a draft too 80 heavy for the closed top and that a smaller flue would have to be provided therefor. This would, offhand, appear to dictate the neces- 85 sity for two separate and distinct flues. However that would be impractical for obvious reasons. The same result is arrived at in a different way according to the present invention as described hereinafter.

The neck 19 to which the flue conduit 20 90 is connected extends through the burner box back wall 21 as indicated. Bolts 22 serve to fasten the flanged lower end of the conduit 20 to the neck 19. The conduit 20 is preferably 95 but not necessarily of an approximately triangular form, tapering from a comparatively wide lower inlet end 23 of nearly the full width of the cooking top to a relatively re- 100 stricted upper outlet end 24 communicating with the flue proper, shown at 25. The com-

munication of the conduit 20 with the flue 25 is afforded through the end of a manifold or intermediate conduit 26 as clearly appears in Fig. 2. The flue 25 is of appreciably larger cross-sectional area than the outlet end 24 of the conduit 20 as will be readily apparent. The capacity of the conduit is determined accurately to suit the requirements of the closed top whereas that of the flue 25 is determined to suit the requirements of the oven section 5. The latter has connection through an outlet opening 27 and neck 28 with the conduit 26 and through the latter with the flue 25. The restriction of the outlet end of the conduit 20 does not cause a sluggish flow of the waste products of combustion from the closed top because of the fact that the outlet end 24 of the conduit is disposed directly beneath the inlet end of the flue 25 and hence is subject to the good draft provided thereby.

In operation it is found that the flue connections just described result in perfect combustion at both the front and the back burners at all loads from the lowest to the highest. 10 There is never any evidence of "floating", due to too much or not enough secondary air reaching the burner flames. Furthermore, it will be apparent that the construction and arrangement are simple and inexpensive and 15 easy to assemble.

I have illustrated the use of shields at 29 and 30 covering the conduits 20 and 26 respectively. These shields are mounted on the backs of the conduits in spaced relation 20 thereto as by means of spacers 31 and bolts 32. When shields are provided in this way the stove may be placed close to the wall without danger of scorching the same. This is 25 obviously due to the fact that air is free to circulate between the back of the conduits and 30 the shields.

I claim:

1. A gas range having a closed cooking top, a shallow combustion and flue chamber beneath the cooking top to which air is admitted only through secondary air openings and having a relatively wide outlet opening across one end, Bunsen burners arranged so that their flames project through said secondary air openings and entrain secondary air for supporting combustion for heating the cooking top, an upright flue conduit having its lower end corresponding in area and connected to the said outlet opening and having its upper end restricted to provide an outlet opening of predetermined area, and a flue structure into which said restricted outlet end of the upright flue discharges and which is adapted to be connected to a chimney or 10 conduit for carrying the products of combustion away, said flue structure having an inlet opening separate from the upright flue communicating with the atmosphere, the area of 15 said restricted outlet opening being so portioned with respect to the secondary air

inlet openings of the combustion chamber as to effect a balanced elimination of products of combustion without excess of secondary air entrainment under varying draft and atmospheric conditions.

2. A gas range as set forth in claim 1, including an oven and in which the inlet opening in the flue structure separate from the upright flue communicates with the atmosphere through the intermediary of the flue for carrying the products of combustion from the oven, and which flue discharges into the flue structure defined in said claim.

In witness of the foregoing I affix my signature.

STANLEY H. HOBSON.
